Primary Examiner — Selina Sikder(74) *Attorney, Agent, or Firm* — Studebaker & Brackett PC(57) **CLAIM**

The ornamental design for a remote controller for air conditioner, as shown and described.

DESCRIPTION

FIG. 1 is a front, top and right side perspective view of a remote controller for air conditioner showing our new design;

FIG. 2 is a front view thereof;

FIG. 3 is a top view thereof;

FIG. 4 is a bottom view thereof;

FIG. 5 is a right view thereof; the left side view being a mirror image thereof; and,

FIG. 6 is a reference perspective view showing state in use thereof.

The parts shown in the broken lines do not form part of the claimed designs.

1 Claim, 5 Drawing Sheets(56)
